his ATTORNEY

UNITED STATES PATENT OFFICE.

HARVEY J. LOUNSBURY, OF CHICAGO, ILLINOIS, ASSIGNOR TO WILLIAM H. MINER,
OF CHAZY, NEW YORK.

YOKE.

1,355,987.

Specification of Letters Patent. Patented Oct. 19, 1920.

Application filed April 3, 1919. Serial No. 287,293.

To all whom it may concern:

Be it known that I, HARVEY J. LOUNSBURY, a citizen of the United States, residing at Chicago, in the county of Cook and State 5 of Illinois, have invented a certain new and useful Improvement in Yokes, of which the following is a full, clear, concise, and exact description, reference being had to the accompanying drawings, forming a part of 10 this specification.

This invention relates to improvements in yokes.

The object of the invention is to provide a yoke which is readily detachable from 15 standard draw bars of railway draft riggings and wherein provision is made for a radial or swivel action of the draw bar with respect to the yoke.

In the drawing forming a part of this 20 specification, Figure 1 is a part vertical sectional view, part side elevation, of a yoke embodying my improvements. Figs. 2 and 3 are sectional views taken on the lines 2—2 and 3—3, respectively, of Fig. 1. And 25 Fig. 4 is a detail perspective showing the details of the coöperating bearing surfaces of the strap and head, which together form my improved yoke.

In said drawing, the improved yoke is 30 shown as comprising a head A and a yoke proper or strap designated generally by the reference B. The head A is of hollow substantially rectangular form and has upper and lower horizontal walls 10—10 and vertical side walls 11—11. The latter are provided with forward extensions or wings 12, slotted, as indicated at 13, to receive a coupler key by which the head may be detachably connected to a standard draw bar, indicated by dotted lines in Fig. 1 at 14. The 35 wings 12 are tapered and provide upper and lower edges 15—15 which diverge from the front ends of the head to levels in alignment with the upper and lower walls of the head, as most clearly shown in Figs. 1 and 4. Each of the upper and lower walls 10 is provided, on its front edge, with an arcuate bearing surface 16, which extends from side to side of the head, thereby providing a 40 maximum wearing and bearing surface.

The yoke proper or strap B is shown as formed in two parts, designated 17—17. Each of these parts provides a horizontal arm 18 of the strap and a half, 19, of the 45 rear connecting portion of the strap. The

two parts are rigidly united in any suitable manner—as, for instance, by employing the usual filler plate 20 and outside plate 21 and connecting rivets 22—22. At its forward end each arm 18 is inwardly offset, as indicated at 23, and, at its extreme end, is provided with an enlarged head 24. Each head 24 corresponds in width substantially to the width of the head A and the same are also thickened vertically, as indicated in Fig. 1, 60 so as to provide an arcuate bearing surface 25 coöperable with the corresponding arcuate bearing surface 16 of the head. As clearly illustrated in Fig. 2, the width horizontally of the arms 18 is considerably less 70 than the interior width of the head A, so that a free and easy relative radial movement between the head A and strap B is permitted. Because of the offsets 23 in the strap B, upper and lower shoulders will be 75 formed, as indicated at 26—26, which are in close proximity to the rear edges of the upper and lower walls of the head A so as to effectively prevent rearward movement of the head A with respect to the strap B. To 80 provide more clearance during the relative radial movements of the head A and strap B, the inner faces of the side walls of the head A may be cut away at an angle, as indicated at 27—27 in the planes of the offset portions 85 23 of the strap B.

As will be seen from an inspection of Figs. 2 and 4, the widened ends 24 of the arms of the yoke strap overlie the edges 15 of the wings of the head A and bear directly thereon. With this construction, it is evident that the front ends of the arms of the yoke strap will always be held in their maximum separated condition and cannot possibly 90 come together and thereby permit accidental 95 disengagement of the coöperating bearing portions of the strap B and head A.

As will be understood by those skilled in the art, the arms of the strap B are spaced apart rearwardly of the head A a greater 100 distance than within the head A in order to accommodate the follower C and associated parts of the shock absorbing mechanism proper.

The parts are assembled as follows: Before the two members 17 of the strap B are connected, they are inserted within the head A from the front thereof, this being necessary on account of the widened ends 24 which would not permit their insertion from 110

the rear end of the head A. After the two parts 17 have been thus assembled with the head A, their rear ends 19 are united in the manner shown in Fig. 1 and hereinbefore 5 described.

With the arrangement shown, I obtain the maximum radial bearing surfaces between the strap B and the head A, while, at the same time, permitting the necessary 10 easy radial action. This is a distinct advantage over certain types of yokes heretofore made, wherein, on account of the relatively small bearing areas between the strap and head, frequent shearing of the bearing 15 lugs or bosses or gibbs on the strap has occurred.

I claim:

1. As an article of manufacture, a yoke for railway draft riggings comprising, a 20 hollow substantially rectangular head, and a yoke strap, the forward ends of the arms of the yoke strap being extended within the head and provided with enlargements of greater width than the interior width of 25 the head, said enlargements and the upper and lower walls of the head having shou-dered engagements, the arms of the yoke strap being upwardly and downwardly off-set at the rear of the head and thereby pro-30 viding shoulders coöperable with the rear edges of the upper and lower walls of the head to prevent relative longitudinal move-35 ment between the head and yoke strap, the arms of the yoke strap being separately formed and rigidly united.

2. As an article of manufacture, a yoke

for railway draft riggings comprising, a hollow substantially rectangular head, and a yoke strap having upper and lower arms, said arms of the yoke strap being separately 40 formed and rigidly united at their rear ends, the forward ends of the yoke arms being inwardly offset and passing within the head, said ends of the yoke strap having enlargements provided on their rear faces with 45 curved bearing surfaces, the forward edges of the upper and lower walls of the head being provided with coöperating curved bearing surfaces.

3. As an article of manufacture, a yoke 50 for railway draft riggings comprising, a hollow substantially rectangular head, and a U-shaped yoke strap having upper and lower substantially parallelly arranged arms, the forward ends of said yoke arms 55 being inwardly off-set and passing within the head, the extreme outer ends of the arms of the yoke strap being laterally extended and provided on their rear faces with bearing surfaces coöperating with the forward 60 edges of the upper and lower walls of the head, said offsets of the yoke arms being so located as to form upper and lower outer shoulders thereon in proximity to the rear edges of said upper and lower walls of the 65 head and coöperable with the latter to prevent relative longitudinal movement between the head and yoke strap.

In witness that I claim the foregoing I have hereunto subscribed my name this 29th 70 day of March, 1919.

HARVEY J. LOUNSBURY.
